UNITED STATES PATENT OFFICE.

AUGUSTUS H. DURBUR, OF BROOKLYN, NEW YORK.

DESIGN FOR A MOLDING FOR PICTURE-FRAMES.

SPECIFICATION forming part of Design No. 23,152, dated March 27, 1894.

Application filed February 3, 1894. Serial No. 499,030. Term of patent 3½ years.

To all whom it may concern:

Be it known that I, AUGUSTUS H. DURBUR, a citizen of the United States, residing at Brooklyn, in the county of Kings and State of New York, have invented and produced a new and original Design for a Molding for Picture-Frames or the Like, of which the following is a specification, reference being had to the accompanying drawings, forming part thereof.

Figure 1 is a front view of a molding showing my design. Fig. 2 is a view of the corner of the same.

My design consists of an ornamentation in relief for a molding suitable for picture frames or the like.

The leading features of the design are ornamental leaves and flowers in relief arranged substantially as shown in the accompanying drawings.

A are the large leaves occupying the full width of the molding and running in the same direction. Between the large leaves A are flowers B. The corner is formed of three leaves sloping in the same direction.

The chief features of my design consist of leaves running in the same direction with flowers B between them; also the leaf arrangement in relief at the corner or corners.

I claim—

The design for a molding for picture frames, substantially as herein shown and described.

Signed at the city of New York, State of New York, this 2d day of February, 1894.

AUGUSTUS H. DURBUR.
